SIGNAL DEVICE FOR THERMOSTATIC SWITCHES

Harry B. Fuge and James W. Memberg, Somerville, N. J., assignors to The Singer Manufacturing Company, Elizabeth, N. J., a corporation of New Jersey

Application May 3, 1944, Serial No. 533,856

5 Claims. (Cl. 200—121)

1

This invention relates to signal devices and more particularly to a signal device for a thermostatically controlled switch.

Switches of this type are often used on electric motors to break the electrical circuit to the motor on a rise of current which would be injurious to the motor. These switches automatically break the circuit to the motor, but in order for the motor to be connected again to the electrical circuit the switch must be reset manually. One of the objects of this invention is to provide a signal associated with the switch for indicating that the circuit to the electric motor has been broken by the thermostatic switch and that the switch must be manually reset before the motor can again be started.

Another object of this invention is to provide a signal device for a thermostatic switch which is built into the push-button of the switch and which does not increase the overall dimensions of the switch. A still further object of this invention is to provide a combined signal device and thermostatic switch which is economical in construction, easy to assemble and may be built as a unit and applied to the electrical device which it is adapted to protect.

With the above and other objects in view, as will hereinafter appear, the invention comprises the devices, combinations and arrangements of parts hereinafter set forth and illustrated in the accompanying drawings of a preferred embodiment of the invention, from which the several features of the invention and the advantages attained thereby will be readily understood by those skilled in the art.

In the drawings—

Fig. 1 is a vertical sectional view taken substantially through the center of a thermostatic switch having our signal device embodied therein.

Fig. 2 is a sectional view taken along the line 2—2 of Fig. 1.

Fig. 3 is a top plan view of the device shown in Fig. 1 with the push-button removed.

Fig. 4 is a side elevation of the push-button showing the lamp encased therein.

Fig. 5 comprises perspective views of the push-button and closure plate therefor.

In the embodiment of the invention selected for illustration, 10 represents a motor casing formed with an aperture 11 which is adapted to receive the thermostatic switch with our improved signal device embodied therein. The switch comprises a cup-shaped base member 12 made of dielectric material and having diametrically opposed laterally extending ears 13 each be-

2

ing formed with U-shaped slots 14 which are adapted to receive screws for the purpose of removably securing the base in the aperture 11 of the motor casing 10.

5 The base 12 is provided with holes in which the contacts or terminal lugs 15, 16 and 17 are placed. The lugs 15, 16 and 17 have their upper ends bent over to form flat contact plates 15', 16' and 17' and electrically connecting the contact plates 15' and 16' is a resistance heater wire 38. A bimetallic disk 18 is disposed within the upstanding walls of the cup-shaped base 12 and is provided with two contacts 19 and 20 on its lower face. The disk 18 is held in position by means of a screw 15 21 which is threaded into the base member 12. When heated, the disk 18 has the characteristic of snapping from the convex position shown in full lines in Fig. 1 to the opposite convex position shown in dotted lines in Fig. 1. However, the disk 20 is unable, upon cooling, to snap back to its original position and must be moved back manually. From the above it will be understood that when the disk is in the position shown in full lines in Fig. 1, the contacts 19 and 20 are in engagement with the bent over ends 15' and 17' of the terminals 15 and 17 and the electric circuit to the motor is closed through the disk 18, and when the disk is in its dotted line position the contacts 19 and 20 are out of engagement with the terminals 30 15 and 17 and, consequently, the electric circuit to the motor is open. The above described switch is old and well known and further detailed description is deemed unnecessary.

Located at one side of the bimetallic snap-acting disk 18 and extending through the reduced portion 11' of the aperture 11 is a push-button 22 made of translucent material. The push-button 22 is dome shaped and is formed with an enlarged laterally extending foot portion 23 which 40 is provided with diametrically arranged narrow slots 24. Immediately below each of the slots 24 is a second slot 25 which is somewhat wider than the slot 24. Located within the push-button 22 is a glow lamp 26 provided with spaced electrodes 45 27 and leading in wires 28. The free ends of the wires 28 are soldered or otherwise electrically connected to the ends of the conductors 29 located within the push-button. The conductors 29 extend through the slots 24 in the base of the push-button and their ends are bent over as indicated at 30 so that they lie along the peripheral wall of the foot portion 23. The bent over ends of the conductors are in contact with the resistors 31 which are embedded in the inner peripheral wall of the cup-shaped base member 12

and are in engagement with the terminals 15 and 17. Fitted into the lower portion of the foot portion 23 is a plate 32 made of insulating material and formed with diametrically opposed ears 33 which fit into the slots 25 formed in the foot portion 23 of the push-button. The plate 32 is provided on its lower face with three buttons 34 which are adapted to engage the disk 18 and force it from the dotted line position to the full line position to close the circuit to the motor when the push-button 22 is depressed. From the above it will be understood that the push-button and light may be built as a unit and applied to the thermostatic switch.

In order to guide the push-button 22 and prevent it from turning relative to the base 12, the outer periphery of the foot portion of the button is provided with two closely spaced lugs 35 which are located on opposite sides of a rib 36 which projects from the inner wall of the cup-shaped base member 12. This arrangement prevents the push-button from turning relative to the base and thus maintains the bent over ends 30 of the conductors 29 in contact with the resistors 31. In order to maintain the push-button 22 centrally of the upstanding walls of the base 12 the foot portion of the push-button is provided with a lug 37 located diametrically opposite the lugs 35. From the above it will be understood that the bent over ends 30 of the conductors 29 and the lugs 35 and 37 maintain the push-button 22 in spaced relation with the upstanding wall of the cup-shaped base 12.

In one use of our improved combined signal device and thermostatic switch, the switch is applied to an electric motor and if the rotor of the motor should stall, or if the motor should be abnormally overloaded, the combined heat from the motor, the resistance wire 38 and the heat generated by the resistance of the thermostatic disk 18 causes the disk 18 to snap from the full line position shown in Fig. 1 to the dotted line position. It will be observed that the glow lamp 26 is at all times electrically connected to the terminals 15 and 17 through the resistors 31 and electrical conductors 29. However, when the disk 18 is in full line position the terminals 15 and 17 are electrically connected through the disk 18 and as the disk offers considerably less resistance to the passage of the current than the resistors 31 the lamp does not glow. When the disk 18 snaps to the dotted line position the terminals 15 and 17 are no longer electrically connected by the disk and sufficient current will pass through the resistors 31 to cause the lamp 26 to glow and thereby indicate that the thermostatic switch has opened and must be closed before the motor can be started. After the disk has snapped to its open circuit or dotted line position, the push-button 22 may be pushed towards the base 12 so that the button 34 on the plate 33 will engage the upper face of the disk 18 and flex the disk so that it will return to closed circuit position.

From the above it will be observed that the signal for the thermostatic switch has been placed within the push-button and that the overall dimensions of the switch have not been increased. It is apparent that the above described construction has a wide variety of uses, and it will be understood that the form, and arrangement of the several elements employed may be varied. Therefore, the privilege is reserved of resorting to all such legitimate changes therein

as may be fairly embodied within the spirit and scope of the appended claims.

Having thus set forth the nature of the invention, what we claim herein is:

- 6 1. In a thermostatic device having a base-member carrying spaced terminals and a heat responsive snap acting bimetallic disk bridging the space between the terminals and having an initial circuit closing position and an open circuit position to which it moves by thermal action, the improvement which comprises the provision of a push-button located on one side of said disk for moving said disk from open circuit to closed circuit position, resistance elements embedded in said base member and in electrical contact with said terminals, conductors carried by said push-button and slidably engaging said resistance elements, and a glow lamp disposed within said button and electrically connected to said conductors.
- 10 2. In a thermostatic device having a base-member carrying spaced terminals and a heat responsive snap acting bimetallic disk bridging the space between the terminals and having an initial circuit closing position and an open circuit position to which it moves by thermal action, the improvement which comprises the provisions of a push-button made of translucent material and located on one side of said disk for moving said disk from open-circuit to closed circuit position, two oppositely disposed resistance elements in electrical contact with said terminals, conductors carried by and movable with said push-button, said conductors having a sliding engagement with said resistance elements, and a signal lamp disposed within said push-button and electrically connected to said conductors.
- 15 3. In a thermostatic electric switch comprising a base-member carrying spaced stationary electrical contacts, a heat responsive snap-acting disk located on one side of said contacts and adapted to engage said contacts in normal circuit closing position and to move away from said contacts to an open circuit position upon an abnormal rise in temperature, the improvement which comprises the provision of a pair of spaced resistors electrically connected to said contacts, a push-button located on the side of said disk opposite to the contacts, conductors carried by said push button and contacting said resistors, and a signal light carried by said push button and electrically connected to said conductors.
- 20 4. In a thermostatic electric switch comprising a base-member carrying spaced stationary electrical contacts, a heat responsive snap-acting disk located on one side of said contacts and adapted to engage said contacts in normal circuit closing position and to move away from said contacts to an open circuit position upon an abnormal rise in temperature, the improvement which comprises the provision of a pair of spaced resistors electrically connected to said contacts, a translucent hollow push-button located on the side of said disk opposite to the contacts, said push-button being confined to a right line movement, electrical conductors passing through the walls of said push-button and having their extending ends in engagement with said resistors, and a glow lamp located within the hollow push-button and electrically connected to said conductors.
- 25 5. In a thermostatic electric switch comprising a base-member carrying spaced stationary electrical contacts, a heat-responsive snap-acting disk located on one side of said contacts and

adapted to engage said contacts in normal circuit-closing position and to move away from said contacts to an open circuit position upon an abnormal rise in temperature, the improvement which comprises the provision of a pair of spaced resistors electrically connected to said contacts, a hollow push-button located on the side of said disk opposite to the contacts, said push-button being confined to a right line movement, electrical conductors passing through the walls of said push-button and having their free ends in engagement with said resistors, and a glow-lamp located within the hollow push-button and electrically connected to said conductors.
